(57) **CLAIM**

The ornamental design for a baseball bat barbecue fork, as shown and described.

DESCRIPTION

FIG. 1 is a perspective view of my design for a baseball bat barbecue fork;

FIG. 2 is a front elevational view of my design for a baseball bat barbecue fork;

FIG. 3 is a rear elevational view of my design for a baseball bat barbecue fork;

FIG. 4 is a right side elevational view of my design for a baseball bat barbecue fork;

FIG. 5 is a left side elevational view of my design for a baseball bat barbecue fork;

FIG. 6 is a top plan view of my design for a baseball bat barbecue fork; and,

FIG. 7 is a bottom plan view of my design for a baseball bat barbecue fork.

The broken lines in the drawings are for illustrative purposes only and do not form part of the claimed design.

No particular length is being claimed and any portion of the article between the break lines forms no part of the claimed design.
